MENDEL OSNOS, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY

WIRELESS SYSTEM

Application filed November 30, 1925, Serial No. 72,132, and in Germany December 17, 1924.

The purpose of this invention is to provide a system for increasing the sensitivity of telegraphy and telephony work and more particularly in wireless systems such as disclosed and described in my co-pending application Serial No. 64,245, filed October 22, 1925.

The present invention provides means adapted to increase the sensitivity of systems comprising static frequency changers in telegraphy or telephony with what is known as a keying or telephony choke, and the term "keying choke" as hereinafter used will be broadly to a choke adapted to control an alternating current by means of a direct current. For this object, conformably with the invention, the action of the keying choke is aided favorably by the simultaneous influencing of the magnetic state of the frequency changer. This may be utilized profitably in such cases where the paths of the control currents, both in the keying choke as well as in the frequency changer, possess time-constants which are substantially immaterial. This is true when the keying choke according to my application Serial No. 64,245, filed October 22, 1925, and the frequency changer according to the disclosure in my U. S. Patent No. 1,664,044, granted March 27, 1928, are both made of iron-enveloped copper conductors passed jointly by the high frequency current as well as the controlling current.

The accompanying drawings illustrate one embodiment of the idea underlying the invention, wherein Fig. 1 illustrates one of the circuit arrangements capable of carrying out the invention;

Fig. 2 illustrates by a considerably enlarged view for clearness of illustration a section on the line 2-2 through the frequency changer *t*; and

Fig. 3 illustrates by a considerably enlarged sectional view a section through the keying choke *d* on the line 3-3.

Now to refer particularly to the drawings, the frequency changers are connected by way of condensers *C*¹ *C*¹ with a primary circuit I, and through condensers *C*² *C*² with a secondary circuit II, and consists in this case

of two like parallel connected parts *tt*, and the same being most suitably made of copper conductors enveloped by a coat of iron as disclosed in my above named U. S. Patent No. 1,664,044. The keying choke consists of two like halves *dd*, each half being arranged in series with the respective half of the transformer *t*. The choke also preferably consists of copper conductors surrounded by little iron disks conformably with application Serial No. 64,245, filed October 22, 1925.

The quadrangle which is made up of the two halves of the frequency changer *tt* and the two keying choke halves *dd*, is supplied with direct current in two diagonals thereof, one diagonal receiving a constant direct current from battery *b* through choke coil *f*, while the other diagonal is fed with current thru a control element *m* in the form of a modulator, key or a similarly functioning apparatus. To obtain full power in the antenna circuit (not shown) which may, if desired, be coupled to the secondary circuit II through any well known form of coupling means, the current in the controlling element *m* must be of a value equal to that of the current in the battery *b*. If the two currents from sources *b* and *m* are of equal value it is clearly seen that these currents may be made to balance one another inside the halves of the frequency changer *tt*, so that there exists there no longer any additional magnetization of the iron by properly choosing the direction of the current flow from sources *b* and *m*. Under the above condition, in the choke halves *dd* the two currents become additive to one another, so that on account of the high saturation in the iron the two choke halves *dd* come into consideration neither as ohmic nor as inductive resistances.

For interruption of the aerial power the current of the control element is disconnected, or, most preferably, reversed in polarity, with the result that the two direct currents will then become additive in the transformer *tt*, and diminish its useful power, while at the same time they balance each other in the choke *dd*. The coil then acts as a considerable ohmic and inductive resistance with reference to the high frequency currents.

The above features may be briefly set forth by stating that under a condition with the key or modulator m open, so that the only direct current saturation in chokes dd and frequency changers tt is from battery b , the chokes dd are of relatively high impedance because the direct current supplied as insufficient to bring the saturation of the iron up to the point of complete magnetic saturation. On the other hand, the frequency changers tt will be of a relatively low impedance since the iron in them becomes saturated with a smaller amount of direct current and can even be brought up to saturation by the alternating current from the input side I , since it is possible to completely saturate the iron wrapper of the frequency changer within an alternating current cycle. The next consideration is the harmonics developed by the frequency changer, and the tendency seems to be to produce even harmonics, which will hold even if the direct current is insufficient to carry the point of saturation well up beyond the knee of the saturation curve. It must here be noted, however, that the harmonics developed tend to be different in accordance with whether the direct or alternating current produces the magnetic saturation in the iron wrapper. Upon closing the key or modulation circuit m so that the direct currents add in the chokes dd and oppose in the frequency changers tt it is readily seen that the effects will be opposite from those above stated which means that chokes dd are of relatively low impedance since currents from b and m are added in the keying chokes, the frequency changer will be of relatively high impedance since currents from b and m oppose each other and are, therefore, neutralized, and the harmonics developed will tend to be odd since they are then produced by the saturation of the alternating current, because with opposing currents from b and m the iron wrapper of the frequency changer is not saturated. The thickness of the iron layer in the frequency changer is governed by the wave length of the current supplied thereto. Where the wave lengths are comparatively small, it is recommendable to use a thin layer, while when they are greater, the layer will be correspondingly heavier. On the drawings I have indicated the direction of the current flow from the battery b through the frequency changer and choke by full line arrows and the currents from the modulator m by dotted line arrows and it is thus seen that for conditions when the modulator circuit m is closed that the currents from the sources m and b will add together in the chokes dd and oppose each other in the frequency changers tt . Having thus described my invention, what I claim is:

1. The method of increasing sensitivity in

wireless systems comprising series connected frequency changers and keying chokes which includes impressing a saturating direct current on said frequency changers and keying chokes, and simultaneously and oppositely changing the saturation of said frequency changers and keying chokes. 70

2. In combination, a frequency changer and series connected keying choke, and means for simultaneously and oppositely changing the magnetic saturation of said frequency changer and keying choke. 75

3. In combination, a frequency changer provided with a copper core and thin outer magnetic material, a keying choke provided with a copper core and outer magnetic layer, a source of direct current traversing said frequency changer and keying choke, and means for simultaneously and oppositely changing the magnetic saturation of the outer magnetic layer of both said frequency changer and keying choke. 80 85

4. In combination, a plurality of frequency changers and a plurality of keying chokes, each of said frequency changers being series connected with respect to a keying choke and each frequency changer and series connected keying choke being parallel connected with respect to the other frequency changers and keying chokes, means for introducing a saturating direct current into said system at diagonally opposite points, and means for simultaneously and oppositely changing the saturation of said frequency changers and keying chokes due to said saturating direct current. 90 95 100

5. In combination, a plurality of frequency changer elements and a plurality of keying choke elements, all of said elements being arranged to form a Wheatstone bridge structure wherein the frequency changer elements are arranged in opposite legs and a keying choke element is in the leg adjacent each of said frequency changer elements, means for introducing a direct current on one diagonal of said bridge, said current being adapted to influence the magnetic saturation of said elements, and means in the second diagonal of said bridge for further controlling the magnetic saturation of said elements. 110 115

6. The combination claimed in claim 5 wherein the controlling means in the second diagonal of said bridge is adapted to simultaneously and oppositely influence the magnetic saturation of said frequency changer and keying choke elements. 120

7. The combination claimed in claim 5 wherein said bridge is arranged across a high frequency system and said variation in saturation of said elements is adapted to influence said high frequency system. 125

8. In combination, a plurality of frequency changer elements, a plurality of keying choke elements, all of said elements being arranged alternately to form the four legs of a Wheat-

stone bridge formation whereby a frequency changer element and a keying choke element is series connected with respect to each other and each frequency changer element and series connected keying choke is parallel connected with respect to a like frequency changer and series connected keying choke element, a direct current source in one diagonal of said bridge, said direct current being adapted to influence the magnetic saturation of said elements, a second direct current in the opposite diagonal of said bridge, said last named direct current being adapted to simultaneously and oppositely vary the magnetic saturation produced in said elements by said first named current, and a high frequency circuit adapted for control by said bridge formation structure.

9. In a high frequency wireless system, a means to increase sensitivity which comprises, a plurality of frequency changer and keying choke elements alternately connected with respect to each other whereby they are adapted to form a Wheatstone bridge arrangement, a source of current in one diagonal of said bridge, said current being adapted to flow through both said frequency changer and keying choke elements and influence the magnetic saturation of the same, and a source of modulating current in the second diagonal of said bridge, said modulating current being adapted to simultaneously and oppositely vary the saturating current in said elements.
